(57) **CLAIM**

The ornamental design for a golf putter, as shown and described.

DESCRIPTION

FIG. 1 is a perspective view of a golf putter showing the design of this invention;

FIG. 2 is an inverted rear view thereof;

FIG. 3 is a top view thereof.

FIG. 4 is a front view thereof.

FIG. 5 is a bottom view thereof.

FIG. 6 is a side view thereof.

FIG. 7 is an opposite side view thereof.

FIG. 8 is an enlarged perspective view thereof; and,

FIG. 9 is an enlarged rear perspective view thereof.

The broken line showing is for illustrative purposes only and forms no part of the claimed design.
